UNITED STATES PATENT OFFICE.

JOSEPH A. HOEGGER, OF JERSEY CITY, NEW JERSEY.

FIXTURE SUPPORT.

Application filed February 17, 1928. Serial No. 619,549.

My invention relates to a support for fixtures and the like and is particularly adapted to securing to a wall or ceiling articles such as bath room accessories, electric light fixtures, and other devices in which it is desirable to so secure the device to the wall that the securing and supporting means shall be concealed from view.

A considerable difficulty has been experienced in securing fixtures of this class to a wall or ceiling in a substantial manner, since, heretofore the usual practice has been to secure such fixtures by means of screws passing therethrough into plugs, expansion bolts, or the like, fastened in the wall. This has involved accurate drilling of relatively small holes which frequently resulted in the cracking or other mutilation of the wall and produced an attachment which lacked strength and was frequently unsightly.

According to my invention I am enabled to firmly attach fixtures to a wall of cement, plaster or similar material, and my improved device is arranged so that the supported fixture is, through the attaching means, drawn into close contact with the wall. When attached no screws or other attaching means are visible.

In the drawings accompanying this specification I have shown—

In Figure 1, a cross sectional view of one form of my invention,

In Figure 2, a plan view thereof,

In Figure 3, a cross sectional view of a modified form of my invention, and

In Figures 4 and 5, vertical and cross sectional views of another modification thereof.

Referring to the drawings, it will be seen that my device comprises a supporting member 1 and a supported member 2, the supporting member being embedded in the wall 3. The wall may be faced with tile 4, or other similar material and the supporting member is inserted in the wall by drilling a relatively large recess 5, which need not be of any exact dimensions, filling said recess with plaster of Paris or other suitable material and inserting the supporting member 1 therein.

The supporting member 1 is provided with lateral extensions 6, of the shape shown, and to permit easy entrance of the lateral extensions through the plaster of Paris while the same is still in a plastic condition, but to prevent the supporting member from

being easily withdrawn therefrom, I prefer to form the lateral extensions with wedge shaped wings 7 since I have found this form to be peculiarly well adapted to the purpose. It will be evident that in forcing the supporting member into the soft plaster of Paris the plaster of Paris may be easily displaced but that when it is attempted to withdraw it it is wedged between the wings 7 and the other portions of the supporting member to form a substantial anchor.

Mounted upon and fixed to the shaft of member 1 is a disk 8 which acts to prevent the material 5 from being forced out of the recess when the end of member 1 is inserted within said recess. The disk 8 also serves to limit the positioning of the entire member 1, which, as has before been stated is the supporting member. As shown in Fig. 2, the disk 8 may, and preferably does have a lug or lip 9 formed on the edge thereof.

The lug or lip 9, it will be obvious, serves to position the supported member 2 and to prevent rotation of the latter, by being fitted within a recess 9' formed in member 2, as clearly shown in Fig. 2. It will also be obvious that if the member 1 is embedded in the wall with regard to the position of this lip 9, the member 2 will have a correspondingly correct position when attached to the member 1. The supported member 2 is adapted to cover the exposed portion of the supporting member as shown in the drawings, and is provided with suitable means, such as set screw 11, for engaging the supporting member. The latter adjacent its exposed end is formed with a taper which may take the form of an annular groove 13 as shown in Fig. 1. The arrangement is such that the tightening set screw in engagement with the taper will force the supported member in the direction of the wall and thus insure a tight fit between the supported member and the wall. It will also be noted that all of the fastening means are covered by the flange on the supported member, and that the only fastening member exposed is the head of the set screw 11, which may be put in an inconspicuous position.

When desired, a portion of the same fastening means may be used, as shown in Fig. 3, in which modification the disk or plate 8 is attached to the wall by means of screws 12, and the anchor portion of the supporting member omitted.

The modification in Fig. 3 is adapted for use on wood or metal, or other substances in which screws can obtain a firm hold and which it is inconvenient to drill and fill with 5 plaster as described above in connection with the modification of Fig. 1.

If desired, the lip 9 may be omitted and the set screw or other means may be used to perform the functions of the lip as well 10 as the other functions performed by it. Such an arrangement is illustrated in Figs. 4 and 5 in which modifications a tapering slot 13 is cut in the supporting member, with which slot the set screw or other means 15 carried by the supported member cooperates. It will be understood that this modification is applicable equally to the device shown in Figs. 1 and 3 and that, if additional precautions against rotation are desired to be 20 taken, the lip may be used as well. If the modification of Figs. 4 and 5 is used, the disk 8 may be entirely omitted or a laterally extending pin 14 or other similar device for positioning the supporting member may 25 be used, although I find the disk 8 useful because it positions the supporting member normal to the line of the wall without the exercise of any great care on the part of the user. 30 While I have only described the forms of my invention which I prefer and have found use for in practice, I do not wish to confine myself thereto as it will be evident to those skilled in the art that many modifications 35 may be made without departing from the spirit of my invention.

It will be noticed that by a very simple structure I attain important results, that is, I get an easy, rigid and permanent assembly. In fixture supports, generally, the supported member has been inclined to wobble more or less in some cases to a considerable extent and in some cases only slightly on its supporting member. This wobbling ultimately results in the supported member becoming loose, either by disturbing the support or by loosening the fastening screw and the fixture ultimately falls apart, or becomes shaky or ugly in appearance. Where 45 the two parts are fastened together by a set screw going through a part of the supported member and into the supporting member, as, for example, in the structure shown in the patent to Wells No. 1,276,463 of 50 August 20, 1918, it is difficult to have the fastening or binding screw register accurately with the hole in the stem, which it is supposed to enter and therefore it is difficult to assemble the structure. Moreover, in a structure of this kind there is likely to be 55 more or less play at the base of the supported structure and between it and the wall with which it abuts, so that this will cause vibration and wobbling. In other structures the 60 stem of the supporting member has been 65

made in two pieces to provide for expanding the stem, and, to a slight extent, for adjustment of the supported member, but structures of this kind are undesirable because of the fact that the stem does not transversely 70 fill the socket of the supported member as it should and reliance has to be had on the fastening screw, and wobbling and vibration result.

Furthermore, the multiple part structure 75 is objectionable because of the expense and the fact that the parts are likely to be improperly fitted or become displaced or lost in shipment. All these difficulties are overcome by my improved structure. 80

It will be noticed that the stem 1 is of the same cross-sectional shape and transversely fills the socket of the member 2 and that the inclined surface of the stem, when engaged by the screw 11, causes the base of the part 85 2 to be brought into firm contact with the adjacent wall so that the parts are held against possible loosening. This rigidity of structure is further enhanced by the fact that the lip 9 on the edge of the member 8 90 engages a complementary part 9' in the member 2, so that when the latter is positioned it cannot turn and it cannot move lengthwise. To get at this result it has sometimes been the practice to have a lug 95 on the face of the part marked 8, corresponding with a complementary socket in the wall of the member 2, but this structure is objectionable for the reason that it is difficult in practice to have the parts always register 100 and to bring them into proper connection. By having this lip on the edge of the member 8, however, it is a simple matter to turn the member 2 so that the recess 9' will register with the part 9, and thus when the structure is erected there is no possibility of the fixture turning or moving axially and, consequently, the erection of the parts is easy 105 and permanent.

What I claim is:

1. A fixture support comprising a supporting member having a rigid one-piece stem with a recessed part, the outer wall of which is inclined towards the base of the stem, means for attaching the stem to 115 a support, a supported member having a socket which fits over the stem of the supporting member so that the stem substantially fills the socket transversely, and a fastening member carried by and adjustable in the supported member intersecting the socket and impinging on the outer inclined wall only of the recess of the stem thereby moving the supported member endwise towards its base. 120

2. A fixture support comprising a supporting member having a rigid one-piece stem with a circumferential recess therein, the outer wall of the recess being inclined toward the base of the stem, means for at- 125 130

taching the stem to a support, a supported clinched wall only of the recess of the stem member having a socket which fits over the stem of the supporting member so that the stem substantially fills the socket transversely, and a set screw carried by and adjustable in the supported member intersecting the socket and impinging on the outer in-

thereby moving the supported member end-
wise towards its base. 10
In testimony whereof, I have signed my name to this specification this 5th day of February, 1923.

JOSEPH A. HOEGGER.
